UNITED STATES PATENT OFFICE.

EUGENE G. BURKS AND NEENIAN HAYES, OF BIRMINGHAM, ALABAMA.

COAL-WASHING APPARATUS.

1,112,976.

Specification of Letters Patent.

Patented Oct. 6, 1914.

Application filed October 15, 1913. Serial No. 795,302.

To all whom it may concern:

Be it known that we, EUGENE G. BURKS and NEENIAN HAYES, citizens of the United States, residing at Birmingham, in the county of Jefferson and State of Alabama, have invented certain new and useful Improvements in Coal-Washing Apparatus; and we do hereby declare the following to be a full, clear, and exact description of the invention, such as will enable others skilled in the art to which it appertains to make and use the same.

The present invention relates to a settling apparatus for treating wash water from washed coal, and has for its purpose to provide an arrangement whereby to recover the coal dust which is usually carried off and lost with the wash water in the method and apparatus now employed.

The further purpose of the invention is to construct a form of apparatus wherein the water for separating the coal is purified or cleared and used over and over progressively with the separating operation, to the end of saving the expense of tankage, and other losses and damage incident thereto.

The method of treating the wash water from washed coal as now carried out consists generally in conveying the same to settling tanks where it is subjected to the action of a constantly flowing stream of water which floats off the foreign matter from the coal, and the coal accumulates or settles in the bottom of the tank from where it is removed by suitable conveyers, usually of the endless type. With this arrangement the wash water in running off carries with it much coal dust which is lost; and there is the further disadvantage that this coal dust is deposited on the banks of the running stream, with the result that it seriously injures the soil and thus brings the coal operators liable to suit for the damage done.

The method disclosed herein seeks to avoid the foregoing disadvantages, and the accompanying drawing illustrates in part section and part elevational view the construction of the apparatus employed.

Referring to the apparatus in detail, the same consists of one, or a pair of settling tanks 1 and 2 suitably mounted on a supporting structure 3, and adapted to hold the wash water A delivered thereto from the pump well 4 located between said tanks, as shown. The tanks are provided with endless conveyers 5 and 6, respectively, for car-

rying off the washed coal which is fed to the apparatus by means of the sluices 7 and 8. The foregoing described apparatus is of known type and is in general use, and no claim is therefore made to the same in the present case.

In the use of the settling tanks 1 and 2, or just one of them as the case may be, fine coal dust, which is not carried away with the wash water accumulates or cakes until the deposit has to be removed by a separate washing operation, since the same cannot be carried by the conveyer, by reasons of being out of its path of operation, and of the tendency of such dust to stick to the sloping sides of the tank as at present used. To avoid this, a separate or independent vessel is located within each tank and forms the coal receiving and delivering receptacle. Each of said vessels is constructed of spaced walls 9 and 10, having perforations 11 through which the wash water may freely pass.

A suitable filtering substance 12, such as coal, slag, charcoal, coke, or other like material, is contained within the space provided by the walls of the vessel, and has for its purpose to filter or clear the water of all coal dust which is held in suspension by the water percolating through the apertures 11. By this provision the coal dust is kept within the filtering vessel, and when the same has caked or accumulated to any extent on the walls thereof, it is removed by the buckets of the conveyer in the course of their normal operation.

The means for delivering the filtered water from the settling tanks consists of a pair of spouts 17 which carry off the overflow from said tanks into the pump well, as shown in the drawing. From the pump well 4 the water is carried to the usual jigs 16 through the pipes 16^a and 17^a, and the force pump 18^a. It is proposed, however, to conduct the wash water from the settling tanks directly to the jigs 16 without first delivering the same into the well 4, and to this end pipes 18 and 19 are connected with said settling tanks, and the pipe 16^a by the branch pipe 15. The pipes 18 and 19 are provided with valves 21 and 22, and the pipe 16^a with a similar valve 23, the purpose for which will be obvious. The wash water is re-delivered to the filtering vessels from the jigs 16 by means of the sluice-ways 7 and 8.

Each of the filtering vessels is provided with a pipe 20 of relatively large diameter,

and has for its purpose to provide a means for cleaning out said vessels in the event that there should be an accident to the machinery so that the coal could not be taken up by the buckets of the conveyer.

It is obvious that those skilled in the art may vary the details of construction and arrangement of parts without departing from the spirit of our invention, and therefore we do not wish to be limited to such features, except as may be required by the claims.

We claim:

In a settling apparatus for coal washings the combination of a tank adapted to hold water, and having an over-flow spout; a filtering vessel located within said tank and providing an annular space therewith, said vessel constructed with inner and outer per-

pendicular and perforated walls, and a granular filling between said walls; a sluice for delivering the material to be separated into said filtering vessel; an endless conveyer operable within the filtering vessel for carrying off the material collected therein; a well located adjacent said tank and adapted to receive the over-flow from the tank spout; a pump; and pipes connecting with said pump and well for carrying off the water from the well and delivering same to the sluice, substantially as described.

In testimony whereof, we affix our signatures, in presence of two witnesses.

EUGENE G. BURKS.
NEENIAN HAYES.
